TREATMENT OF HYDROCARBON OILS

Gustav Egloff, Chicago, Ill., assignor to Universal
Oil Products Company, Chicago, Ill., a corpora-
tion of Delaware

No Drawing. Application March 29, 1933,
Serial No. 663,342

4 Claims. (Cl. 196—10)

This invention refers more particularly to the treatment of the lower boiling fractions of crude petroleums which comprise what are known as natural gasolines and straight run gasolines.

5 In a more specific sense the invention has reference to a process of treatment whereby such lower boiling fractions are selectively converted to produce maximum practical yields of hydrocarbons boiling within the range of commercial 10 gasolines, the fractions thus produced having at the same time improved antiknock characteristics.

The term "natural gasoline" is generally applied to gasolines recovered from casinghead gases either by absorption, compression or refrigeration methods and consists principally of paraffin hydrocarbons of from 3 to 6 carbon atoms to wit, propane, butanes, pentanes and hexanes though there may be minor amounts 20 of higher boiling paraffins present and also small percentages of dissolved hydrocarbon gases depending upon the conditions of recovery employed. Similarly products falling within the category of natural gasolines are obtained from 25 vapor recovery systems on crude and in some cases on refined storage. The term as used in the present sense comprises also low boiling hydrocarbon fractions obtained from stabilizer units applied either to straight run gasoline or 30 their corresponding cracked products. The fractions from cracked gasoline stabilizers will contain in addition to paraffin hydrocarbons variable percentages of the corresponding olefins of the same number of carbon atoms. The term 35 "straight run gasoline" as employed within the meaning of the present specification includes gasoline range boiling fractions produced as a result of the primary noncracking distillation of crude petroleums. In the majority of cases such 40 gasolines are all of a predominantly paraffinic character and as such possess a relatively low knock rating which limits their sales value.

The utilization of natural gasolines has been limited on account of their high vapor pressure, 45 which limits the amounts which can be safely blended with higher boiling range fractions without causing vapor lock troubles. Owing to the fact that there has been a greater production of these gasolines than could be absorbed by the gasoline trade practically all of the propane and a 50 large percentage of the butanes is being sold under pressure in cylinders as domestic or welding gas.

Utilization of straight run gasolines is primarily limited by their generally low antiknock 55 value and the principal method of attack for remedying this deficiency has so far been along the line of cracking to increase their antiknock value.

In one specific embodiment the present invention 60 comprises treatment of natural and/or

straight run gasolines in two steps. In the first step they are cracked to produce optimum yields of olefins, and in the second step the olefins are polymerized by contact with phosphoric acid to produce gasoline boiling range hydrocarbons of 5 improved antiknock value.

It is the object of the present invention to produce the most economical yields of gasoline boiling range fractions and at the same time the maximum antiknock value in the products 10 consistent with the yield. To accomplish this dual object necessitates the control of the cracking conditions of the first step to produce maximum yields of olefins for forming polymers boiling within the range of motor fuels, say below 15 437° F. and possessing high antiknock characteristics, usually about 50% higher than iso-octane which is at present used as a standard of reference. To limit the reactions of decomposition of low boiling paraffins to the production of high 20 yields of olefins rather than compounds of ring structure usually requires relatively high temperatures, moderate to low pressures and short time factors since the olefins are produced by initial decomposition reactions apparently cor- 25 responding to the splitting of straight chain hydrocarbons to form equivalent molecules of paraffins and olefins of one-half the molecular weight. This theory of the central scission of straight chain paraffins is convenient in explain- 30 ing many of the observed results obtained in cracking paraffin hydrocarbons though it may not be entirely adequate to cover all cases or all types of products.

The conditions chosen for initially cracking any 35 particular low boiling paraffinic gasoline will depend primarily upon its boiling range though in general it can be stated that for natural gasolines falling under the generally accepted term that temperatures of from 1100 to 1500° F., pressures 40 of from atmospheric to as low as 50 mm. of mercury absolute and time factors of less than one second comprise the usual range of operating conditions which may be varied to suit individual cases.

In the case of straight run gasolines which may be of higher mean boiling range than natural 45 gasolines, slightly lower temperatures may be employed say within the range of 1000 to 1300° F. and pressures from moderately superatmospheric 50 to some lower limit corresponding to a definite vacuum.

In all cases the low boiling gasolines may be fractionated and individual fractions treated according to their special requirements while the 55 olefins produced are either recombined and treated en masse with the preferred catalyst in the second stage or polymerized separately and blended later.

To assist in elucidating the character of the 60

invention the following table is introduced which shows some of the low boiling olefins along with their formulas and boiling points which may be effectively polymerized to form essentially dimers

5 and trimers by contact with phosphoric acid under controlled conditions:

tions and increase the capacity of commercial equipment though such admixtures must be made with caution if yields of desired products are to be kept high.

In the formation of polymers from olefins, particularly those from mono olefins produced in the

I have found that by suitable control of temperature and the strength and quantity of phosphoric acid employed, the polymerization of the lower boiling olefins produced in the primary cracking step may be halted before the formation of high boiling, resinous or gummy polymers has taken place to any appreciable extent. As a general rule it is only necessary to prevent excessive temperature rise under which conditions ordinary concentrated phosphoric acid may be used corresponding to 85 to 90% by weight of H_3PO_4 . While it is preferred to use the better known and more readily available phosphoric acid it is not outside the scope of the invention to employ any of the known acids of phosphorus alone or in suitable admixtures although the results obtained by these different alternatives will obviously not be exactly equivalent. As a matter of reference the following table is given to show the different acids of phosphorus along with their formulas and their melting and decomposing temperatures.

first step of the process, it is probable that their polymerization is preceded by the formation of phosphoric or phosphorous esters which under the conditions of treatment are relatively unstable and decompose to release the olefin molecules with an increased energy content so that the polymerization reactions result. The exact mechanism of these reactions, however, is not well known and the explanation is not offered as complete.

A marked advantage in the use of phosphoric acid as distinguished from other polymerizing agents such as, for example, sulphuric acid and various metal halides resides in the fact that very little solution of original oil or polymers occurs so that the consumption of acid is small and a given amount may be used repeatedly without the necessity for purification steps which must be employed in removing sludge products from sulphuric acid. Neither phosphoric nor phosphorous acid has any pronounced oxidizing

55 The following table shows the boiling points of dimers of mono olefins from 3 to 6 carbon atoms inclusive, and indicates that they are all within the boiling range of commercial gasolines. It is not given to indicate that only dimers are formed or that such dimers are formed by the union of 60 similar molecules as there is evidence to show that mixed polymers are formed such as, for example, formed by the union of one molecule of propylene with one molecule of butylene.

action under the preferred conditions of treatment so that condensation reactions due to removal of hydrogen or abstraction of water are substantially absent. The polymerizing action of such metal halides as anhydrous aluminum chloride and zinc chloride of varying degrees of hydration is frequently too vigorous to render their use safe in the present connection.

65 The invention is not limited to any particular type of equipment or any specific mode of procedure which may be employed either in the first or the second steps. In the first or cracking step the usual heating coil and reaction chamber hookups of cracking plants may be modified to some extent so that the necessary short time factors corresponding to optimum olefin production are made possible. Thus the heating coils may be considerably shortened and constructed of refractory materials which have substantially no tendency to deformation at high temperature when subjected to external pressure conditions corresponding to vacuum operation.

65	Boiling points of olefin dimers		
Hexylene.....	Dimer of propylene.....	155° F.	
Octylene.....	Dimer of butylene.....	255° F.	
Decylene.....	Dimer of amylylene.....	323° F.	
Dodecylene.....	Dimer of hexylene.....	417° F.	

70 When the olefinic mixtures from the first step are of such a character that there is less tendency for too extensive polymerization to occur, that is, when they are principally mono olefins, minor amounts of sulphuric acid may be mixed with 75 the phosphoric catalyst to accelerate the reac-

The maintenance of vacuum during the heating period is usually best effected by removal of fixed gases from the liquid receiver rather than by the pumping of hot vapors, though obviously the cool fixed gases may contain sufficiently large percentages of recoverable liquids to warrant their recovery by absorption or other method.

In the second step of the process the material to be polymerized may be mixed with phosphoric acid or some other acid of phosphorus either alone or in concentrated aqueous solution and held at suitable temperatures under sufficient neutral gas pressure (to depress vaporization) for a time best determined by trial, the mixture being either mechanically agitated or circulated to and from a closed pressure container. The amount of phosphoric acid or solution thereof which it is necessary to use in any case will depend upon the character of the reacting olefins and the degree of polymerization desired but in general relatively large volumes of acid are used frequently in the ratio of equivalent molecular weight in reference to the particular olefin or mixture of olefins being subjected to polymerization. However, substantially none of the acid is consumed in the treatment and as there is substantially no solubility of reaction products in the acid it may be reused repeatedly without regeneration or purification and, consequently, the amount of acid actually lost in producing polymerization reactions is of a negligible value and due principally to unavoidable accidents.

When it is desired to polymerize olefin mixtures containing large percentages of propylene and the butylenes which are gaseous at ordinary temperatures, they may be pumped into a pressure treater containing the phosphoric acid during agitation of the latter or they may be preliminarily compressed to liquid and handled in the same way as the amylanes or other olefins which are liquid at the temperature of treatment.

As an example of the application of the process to the more efficient utilization of natural gasolines, the following is given though it is merely selected from a large number of other examples of a similar character.

A natural gasoline produced by compression and absorption of casinghead gases in the field may have the following approximate composition:

Composition of natural gasoline

		Percent
Ethane.....	C ₂ H ₆	30
Propane.....	C ₃ H ₈	25
Butanes.....	C ₄ H ₁₀	20
Pentanes.....	C ₅ H ₁₂	15
Hexanes.....	C ₆ H ₁₄	5
Higher paraffins.....	C _n H _{2n+2}	

This gasoline may be subjected to cracking conditions of 1500 to 1600° F., and 100 mm. absolute pressure for a time of 0.02 seconds to produce approximately 30% by weight of readily condensable liquids consisting of 50% olefins such as amylanes and 70% by weight of a gas having the following composition:

Composition of cracked gases

		Percent
Hydrogen.....	CH ₄	10
Methane.....	C ₂ H ₆	5
Ethane.....	C ₃ H ₈	8
Ethylene.....	C ₂ H ₄	10
Propane.....	C ₃ H ₈	22
Propylene.....	C ₃ H ₆	13
Butanes.....	C ₄ H ₁₀	17
Butylene.....	C ₄ H ₈	5
Pentanes.....	C ₅ H ₁₂ & higher.....	

The liquid portions of the cracked products from the first step may be thoroughly agitated with about 20% by volume of 89% phosphoric acid and the gaseous products passed therethrough at a slow rate to insure most effective action. By this procedure there may be produced on a basis of the original gasoline approximately 70% of a mixture of hydrocarbons boiling within the range of gasoline as from 100 to 415° F. having an octane number of 110 and consisting of the pentanes and hexanes still remaining in the cracked mixture plus the polymers from substantially all of the olefins. Thus whereas only about 40% of the original natural gasoline fraction could be employed as blending material in gasoline mixtures, the product of the present process can be completely blended and the increase in volume of blending material is 50% in addition to the fact that the octane number of the primary and secondary blending materials is in the ratio of about 60 to 110. The net overall economy is evident from a consideration of this data.

The foregoing specification and example have disclosed the nature of the invention and shown its advantages in commercial practice but neither is to be considered in the light of imposing undue limitations on its generally broad scope.

I claim as my invention:

1. A process for increasing the anti-knock value of natural and straight-run gasoline to produce a commercial anti-knock automotive fuel, comprising subjecting said gasoline to thermal cracking conditions of temperature and pressure to form therein polymerizable olefines, and thereafter polymerizing the cracked product by subjecting the same to the action of an acid of phosphorus.

2. A process for increasing the anti-knock value of natural and straight-run gasoline to produce a commercial anti-knock motor fuel, which comprises subjecting said gasoline to thermal cracking conditions of temperature and pressure within a heating zone to effect the formation of polymerizable olefines in the cracked product, and thereafter subjecting the resultant mixture of vaporous and liquid olefines to a polymerizing treatment in the presence of an acid of phosphorus.

3. A process for increasing the anti-knock value of natural and straight-run gasoline to produce a commercial anti-knock motor fuel, which comprises initially subjecting said gasoline to cracking conditions of temperature and pressure within a heating zone to induce the formation of olefines within the cracked product, and thereafter treating the resultant mixture of vaporous and liquid olefines with phosphoric acid to polymerize said olefines.

4. A process for increasing the anti-knock value of natural and straight-run gasoline to produce a commercial anti-knock motor fuel, which comprises initially subjecting said gasoline to cracking conditions under a temperature ranging from 1000° F. to 1500° F. and at substantially atmospheric pressure to form substantial amounts of gaseous and liquid olefines within the cracked product, and thereafter polymerizing the olefine content thereof by contacting the cracked product with phosphoric acid.

GUSTAV EGLOFF.
